ELECTRIC STOVE

Raphael Borza and Helen L. Borza, Yonkers, N. Y.

Application April 9, 1948, Serial No. 20,026

3 Claims. (Cl. 161—1)

1

This invention relates to electric stoves or cooking appliances, and aims to provide certain new, useful and practical improvements including adjustable time-delay circuit opening means whereby the power is automatically turned off at a predetermined time, so that a person may attend to other matters while the food is being cooked with the assurance that it will be cooked for exactly the desired length of time without danger of over- or under-cooking.

The above broad object, as well as additional and more specific objects, will become apparent in the following description, wherein characters of reference refer to like-numbered parts in the accompanying drawings. It is to be noted that the drawings are intended for the purpose of illustration only, and that it is neither desired nor intended to limit the invention necessarily to any or all of the exact details of construction shown except insofar as they may be deemed essential to the invention.

Referring briefly to the drawings,

Fig. 1 is a perspective view of an electric stove illustrating one application or embodiment of the invention.

Fig. 2 is a side elevational view of the same.

Fig. 3 is a front elevational view of the same.

Fig. 4 is a plan view of the same.

Fig. 5 is a sectional view taken on the line 5—5 of Fig. 4.

Fig. 6 is a sectional view taken on the line 6—6 of Fig. 2, showing the time-delay switch in open position.

Fig. 7 is a view similar to Fig. 6, showing the time-delay switch in closed position.

Fig. 8 is a sectional view taken on the line 8—8 of Fig. 3.

Fig. 9 is a vertical longitudinal sectional view through the pneumatic cylinder of the time-delay means.

Fig. 10 is a sectional view taken on the line 10—10 of Fig. 6.

Fig. 11 is a wiring diagram of the stove including the heating elements of both burners and the oven.

Fig. 12 is a sectional view taken on the line 12—12 of Fig. 7.

Fig. 13 is a fragmentary perspective view of the lower end of the slide forming part of the time-delay switch operating mechanism.

Fig. 14 is a fragmentary perspective view of another detail of the said mechanism.

Referring in detail to the drawings, the numeral 10 indicates the housing or casing of the stove, which includes the bottom 11 from which

2

four posts 12 rise. The latter support the front wall 13, side walls 14, and the rear wall 15. The floor 11 extends rearward of the rear wall 13, and a rearwardly extending extension casing or cover 16 is provided to conceal the time-delay switch mechanism described below. A roof or top member 17 is removably secured, as by means of screws 18, to the posts 12.

Opposed inner side walls 19 provide inner frame members to support the heating elements and other interior parts as will be clarified below. The walls 19 are provided with aligned deformations 20 which provide guides and supports for a drawer 21 adapted to be drawn through a suitable opening in the front wall 13.

Supported horizontally between the members 19, in vertically spaced relationship as shown in Fig. 5, are plates or sheets of asbestos 22 having mounted on their opposed sides plates 23 of suitable insulating material such as porcelain. The latter are provided with suitable spaced fixed bobbins 24 on which the oven heating element 25 is wound, and between which the drawer 21 lies when closed. A layer 26 of asbestos is also provided behind the front wall of the drawer 21.

Two burner elements, 27 and 28, are provided in the top of the stove, either of which, for example burner 28, is directly connected through its standard switch 29 across the electrical supply lines 30. The other burner 27, together with the oven element 25, is connected to the supply lines 30 through their respective standard switches 31 and 32 and the time-delay switch described below. A horizontal cross member 33 between the side members 19 supports the burners 27 and 28.

Mounted horizontally against the back wall 15 is a cylinder 34 in which a piston 35, with its rod 36, is slidable. The end 37 of the cylinder is closed, but at that end the cylinder is provided with a standard needle valve 38 manipulated by its screw 39 so that the rate at which air may enter or escape from the cylinder is under control.

A T-shaped collar, having a circular opening therethrough to accommodate the rod 36 slidably therein, is shown at 40, and is locked by means of a screw 41 on the rod 36 in a position intermediate the length of the rod. A link 42 has one end rolled into a sleeve 43 which, by means of a screw 44 threaded into one side of the base of the collar 40, pivotally secures that end of the link 42 to the collar 40. On its free end the link 42 has a hook-like attachment or extension 45 extending outward (with respect to the rear wall

(15). An upright support 46 is secured against the rear wall 15, and pivoted at its bight thereto is an L-shaped lever 47 having the long arm 48 and the short arm 49. The arm 48 is positioned between the link 42 and the wall 15, and the hook 45 extends downward over the arm 47 so that the arm 47 is confined between the hook 45 and the wall 15. A switch lever 50 has one end pivoted at 51 to the wall 15 and passes between the upright 46 and the wall 15, terminating in a concave tip 52. A roller 53, or pulley, is mounted between the upper end of the upright 46 and the wall 15. A flexible cable 54 of any suitable material is trained about the pulley 53, having one end secured to the front end of the link 42 and the other end secured to the switch lever 50 near the forward end thereof.

An L-shaped slide 55 has its long arm 56 provided with spaced vertical slots 57, and by means of screws 58 is slidably mounted against the upright 46. One upper corner of the slide 55 is cut away to leave a projecting tongue 59 and a shoulder 60, the upper surface 61 of the tongue sloping as shown.

When the lever 50 is in the normal raised position shown in Fig. 6, the arm 48 of the lever 47 is nearly horizontal and the arm 49 thereof registers in the corner cut-out of the slide 55. The arm 49 is rounded to form a nose, as shown, the tip of which is adapted to slide on the sloping surface 61 of the tongue 59. Pin-like projections 62 and 63 are provided on the arm 49 of the lever 47 and on the slide 55, and these are connected by a coiled spring 64 normally urging the slide 55 upward and normally urging the lever 47 to turn clockwise (Figs. 6 and 7).

A block 65 of insulating material is attached to the short arm 55 of the slide 55 and extends inward toward the wall 15 and its edge lies in the path of the descending lever 50; thus, in movement of the lever 50 through the arc between the positions shown in Figs. 6 and 7, the lever carries the slide downward the distance between the positions shown in those figures. An insulating block 67 is secured to the wall 15 and is provided with two electric contacts 68 and 69. A metallic button 70 rigid on the end of the block 66 is thus brought down from the position shown in Fig. 6 to that shown in Fig. 7 in which it bridges and closes the circuit between the contacts 68 and 69.

The piston 35 is normally in a position toward the left of its cylinder 34 (Fig. 9). Upon depressing the lever 50 from its upper to its lower extreme positions, it is apparent that the cable 54 will pull out the rod 36 and move the piston 35 to the right, thereby creating a suction in the cylinder tending to restore the piston to its original position. As the hook 45 on the link 42 thus moves to the right, it permits the lever 47 to rotate clockwise owing to the spring 64, and when the lever 50 has depressed the block 66 the slide 55 will have been lowered to close the contacts 68, 69 and also to lower the tongue 59 out of contact with the nose 49 whence the lever 47 swings into the position shown in Fig. 7 wherein the nose 49 prevents raising of the slide 55 by the spring 64. When the lever 50, in the position shown in Fig. 7, is released, the suction in the cylinder 34 will gradually draw the rod 36 inward, whence the hook 45, moving leftward, will gradually swing the lever 47 counter-clockwise and at the same time, because of the cable

54, raise the lever 50, the nose 49 during this time riding down the sloping end surface 61 of the tongue 59. When the nose 49 has ridden off the surface 61, the spring 64 is free to snap the slide 55 upward, thus opening the circuit through the contacts 68, 69 and restoring the lever 50 and the lever 47 to their original positions shown in Fig. 6.

The electrical connections and circuits are shown in Fig. 11, the lines 39 leading to terminal blocks 71 and 72. It is to be noted that the burner 27 is put into use by closing the switch 31, and the oven elements 33 are in use when the switch 32 is closed, in both cases the circuits 10 being through the time-delay switch shown fragmentarily in the wiring diagram at 66, 68, 69, and 70. By closing both switches 31 and 32, both the oven and burner 27 are in use simultaneously with the time-delay switch. A terminal block 15 for connecting various leads on the stove is shown at 73, but for the sake of simplicity the leads have been omitted from the drawing excepting in the wiring diagram.

The following means is provided for controlling the length of time that the switch 68, 69, 70 is to remain closed. A plate 75 is secured to the wall 15, and an L-shaped bracket 74 is integral therewith. A pin 77 has its lower end passing freely through an opening in the horizontal arm 76 of this bracket, and is provided with an enlarged, large-pitch screw thread 78 which is engaged by the end of a screw 79 which passes through the vertical arm 79 of the bracket. A knob 81 on the upper end of the stem 77 serves as a handle to turn the stem, and it is provided with an index mark 82 to be used in conjunction with a graduated dial 83 on the cover 17. It is obvious from Fig. 6 that turning the stem 77 so as to cause it to descend will reduce the time interval during which the said switch is closed, for the tip of the stem forces the link 42 to approach closer to the horizontal position, and the hook end of the link likewise swings the lever 47 closer toward horizontal position, and the closed toward horizontal position that the lever 47 is, the nearer toward the end of the surface 61 of the tongue 59 is the nose 49, whence the latter requires a lesser time to ride off the nose. Reverse rotation of the stem 77 will increase the length of the said time interval.

It is apparent from the above that a practical and useful electric stove having controlled time-delay circuit-opening means in connection with both a burner unit and an oven heating element, has been provided, whereby cooking is substantially simplified.

Obviously, modifications in form and structure 60 may be made without departing from the spirit or scope of the invention.

We claim:

1. Time delay switch closing means for an electric stove comprising a cylinder having a piston slidable therein and having the piston rod of said piston slidable through one end of the cylinder whereby withdrawal of said rod from the cylinder creates a suction in the cylinder tending to restore the rod into the cylinder, a key having one end pivoted to the stove and having the other end free and adapted to be depressed below the level of said rod, a pulley rotatably mounted on the stove above the level of said rod, a link pivoted at one end to said rod intermediate the length of said rod, an L-shaped

lever pivotally mounted at its bight to the stove at a point above the lever of said rod, said lever having a long arm extending approximately horizontally, said link having a hook on its free end slidably engaging said long arm of said lever, the other arm of said lever being relatively short, a vertical slide slidably mounted on the stove in the plane of said lever, generally below said short arm, resilient means normally urging said slide upward and normally urging said lever to swing said short arm against said slide, said slide having a projection thereon engageable by said key during depression of said key to lower said slide, a cable trained about said pulley and having one end secured to said free end of said link and the other end secured to said key intermediate the length of the key for pulling said rod outward from said cylinder upon depression of said key, said resilient means in the lowermost position of said key swinging said short arm over the top of said slide and thereby serving as a stop to prevent rising of said slide, said suction upon release of said key slowly restoring said rod into said cylinder and consequently swinging said lever in the reverse direction and causing said short arm to ride off said top of said slide thereby permitting said resilient means to raise said slide, electrical contacts on said stove, said slide having a contact button thereon but insulated therefrom slidable across said contacts and in the lowermost position of said slide bridging said contacts, said stove having a heating element in series with said contacts and being adapted to have electric supply lines connected in the circuit with said contacts and said element.

2. The device set forth in claim 1, having means for varying the time interval between the depression of said key to said lowermost position and the instant at which said short arm rides off the top of said slide as aforesaid.
3. The device set forth in claim 1, having means for varying the interval of time between the depression of said key to said lowermost position and the instant at which said short arm rides off the top of said slide as aforesaid, said means comprising a pin mounted on the stove substantially at right angles to said rod and spaced therefrom, said link in the normal in-drawn position of said rod lying between said pin and said rod and in contact with said pin, said pin having threads thereon for advancing or retarding the same to swing said link toward said rod or permit said lever to swing said link away from said rod thereby respectively decreasing or increasing said time interval.

RAPHAEL BORZA.
